(57) **CLAIM**

The ornamental design for a convertible tail gate, as shown and described.

DESCRIPTION

FIG. 1 is a front right three-quarter view of a convertible tail gate for a vehicle according to the present invention.

FIG. 2 is a rear left three-quarter view of the convertible tail gate shown in FIG. 1.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a rear right three-quarter view of the convertible tail gate shown in FIG. 1, with the convertible tail gate mounted on a vehicle that is depicted in de-emphasized and halftone portions so as to illustrate the environment structure. These deemphasized portions of the vehicle form no part of the claimed design. More particularly, in FIG. 8, the convertible tail gate of the present invention is shown within broken lines, and any elements shown outside of the broken lines form no part of the claimed invention, but are instead included to show environmental aspects of the claimed invention.

Nevertheless, the broken lines shown in each of FIGS. 1-6 and 8, and which are within the convertible tail gate, show a latch which is an unclaimed portion of the convertible tail gate. The latch forms no part of the claimed design.

1 Claim, 7 Drawing Sheets
